ELECTRIC SEWING MACHINE CABINET

Herbert J. Goosman, Elizabeth, and Richard Kaier, Cranford, N. J., assignors to The Singer Manufacturing Company, Elizabeth, N. J., a corporation of New Jersey

Application May 24, 1935, Serial No. 23,186

10 Claims. (Cl. 311—16)

This invention relates to electric sewing machine cabinets or tables and has for an object to provide a sewing machine cabinet or table with means for detachably supporting a foot-operated type of motor-controller in position for knee-operation, from which position the controller may be readily shifted to conceal the latter when not in use. The invention also aims to provide an electric sewing machine cabinet or table which, when not in use, has the esthetic appeal of an attractive article of furniture, with no conspicuous elements of mechanization and which when opened for use will permit of the operation of the sewing machine motor-controller either by knee or by foot, at the will of the operator.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front elevation of a drop-head sewing machine cabinet or table embodying the invention, Fig. 2 is a fragmentary horizontal section through one corner of the cabinet, showing the motor controller in concealed position. Fig. 3 is a transverse vertical section through the cabinet. Fig. 4 is a transverse section through the controller unit and its support. Fig. 5 is a perspective view of the controller support and Fig. 6 is a perspective view of the rear or bottom face of the controller casing.

In the preferred embodiment of the invention illustrated, the numeral 1 indicates the legs 40 of a drop-head sewing machine cabinet or table having a top 2, end walls 3, a rear wall 4 and a front wall 5 including a hinged section 5', which walls define a cavity below the top 2 for reception of the motor-driven sewing machine head 6, when not in use. The sewing head 6 is hinged at 7 to the table top 2 and may be swung upwardly about the hinge axis 7 to an operative position above the table top. The usual cover leaf 8 covers the table top 2 when the machine head 6 is resting in its lowered position. The sewing head 6 has mounted thereon a driving motor 9 the pulley 10 of which is connected by a belt 11 to the balance wheel pulley 12 of the machine head.

55 Mounted in the right-hand front corner of the cabinet by screws 13 is a bracket 14 having a short leg 15 and a longer leg 16 supporting the hinge pin 17. The longer leg 16 has at its free end a tang 16' which is driven into the front wall 5 of the table to steady the bracket 14 and

relieve the screws 13 of a certain amount of strain to which they would otherwise be subjected.

Mounted on the hinge pin 17 is a swingable controller-supporting member 18 in the form 5 of a sheet metal plate having bent up marginal wall portions 19 and overhanging lips 20 defining a slideway for reception of the longitudinal ribs 21' of the casing 21 of the conventional motor-controller having an operating pedal 22 10 hinged at 23 on the casing 21 and connected to the pull-rod 24 of the usual carbon compression type rheostat 25 housed within the casing 21. A controller of this type is disclosed in U. S. Patent No. 1,777,988, of Oct. 7, 1930. 15

Mounted on one of the side walls 19 of the controller support 18, within the controller-receiving slideway, is a leaf-spring 26 which yieldingly urges the controller casing 21 toward the opposed side wall 19, the width of the slideway 20 being somewhat greater than the width of the controller casing to permit of a certain amount of side play of the controller within the slideway.

The controller casing 21 has struck out from 25 its bottom wall a tongue or lug 27 which engages over the upper end of an inclined tongue or lug 28 struck from the supporting plate 18 and locks the controller casing 21 in operative position within the slideway of the plate 18. 30

To remove the controller unit from the supporting plate 18 it is merely necessary to shift the controller laterally toward the leaf-spring 26 sufficiently to disengage the lug 27 from the end of the inclined lug 28, whereupon the controller 35 may be slid downwardly out of the slideway in the plate 18 and placed upon the floor for foot-operation. To replace the controller in the supporting plate, it is merely necessary to insert the ribbed portion 21' of the controller casing in the 40 slideway of the supporting plate and slide the controller upwardly until the lug 27 snaps past the inclined lug 28 and is locked by the latter in position for knee-operation.

When the outfit is not in use, the plate 18, together with the controller 21, may be swung upwardly about the hinge-pin 17 to the concealed position, shown in dotted lines in Fig. 1, within the cavity of the cabinet where it is retained by the entry of the rounded neb 29 on the leg 16 into 50 the hole 30 in one side wall 19 of the plate 18; being yieldingly held there by the spring 31 which is carried by the plate 18 and engages the leg 15 of the bracket 14.

The plate 18 has fixed to its lower end a rubber foot 32 which rests against one of the table legs 1 when the controller is in pendant operative or full line position Fig. 1, in which position the pedal 22 of the controller is accessible for knee-operation. 60

The controller is connected by a length of conductor cord 33 to the current-receiving plug 34 and is connected in series with the sewing machine motor connector 35 and in multiple with the sewing machine light connector 36, in accordance with the usual practice. The conductor cord 33, which is long enough to reach to the controller when placed upon the floor for foot operation, may be looped and held by the hook 37, Fig. 3, when the controller is placed in the support 18 for knee operation.

We are aware that we are not broadly the first to mount a foot-operated motor-controller on a sewing machine table in position for knee-operation but, so far as we are aware, no one has heretofore accomplished this result in a sewing machine cabinet or table which, when not in use, has the esthetic appeal of an attractive article of furniture and the motor-control mechanization of which is of a disappearing nature yet may be operated either by foot or by knee.

It will be obvious to those skilled in the art to which the invention appertains that modifications may be made in the details of construction and in the forms and relative arrangements of parts without departure from the spirit of the invention which is not limited to such details and matters of form or otherwise than the prior art and the appended claims may require.

Having thus set forth the nature of the invention, what we claim herein is:—

1. The combination with a drop-head sewing machine table having legs, a top, and side wall members defining a cavity below said top for reception of the sewing machine head when not in use, and a foot-operated motor controller adapted to rest for use upon the floor, of a support adapted to detachably carry said motor-controller and mounted in said table to position said motor-controller for operative engagement by the knee of an operator, said support being shiftable with or without the controller to a concealed position within said cavity.

2. The combination with a drop-head sewing machine table having legs, a top, and side wall members defining a cavity below said top for reception of the sewing machine head when not in use, of a motor-controller support permanently mounted in said table and shiftable from an operative position below said cavity to a concealed position within said cavity, and a motor-controller unit of the foot-operated type detachably mounted on said support, said unit including a base adapted to rest for use upon the floor, a rheostat carried by said base, and a member movable toward and away from said base and connected to operate said rheostat.

3. The combination with an electric sewing machine motor-controller of the foot-operated type having a base adapted to rest for use upon the floor, an operating pedal movable toward and away from said base, and a rheostat carried by said base and connected to be operated by said pedal, of a drophead sewing machine table having legs, a top and side members defining a cavity below said top, and a bracket adapted to detachably carry said motor-controller and mounted on said table in position for the pedal of said motor-controller to be engaged by the knee of the operator, said bracket being shiftable to a concealed position within said cavity.

4. The combination with a sewing machine table, of a bracket permanently mounted on said table, a controller support pivotally carried by

said bracket to swing from operative to inoperative position and formed with a slideway, and an electric sewing machine motor-controller having a casing slidably received in said slideway.

5. The combination with a sewing machine table, of a bracket permanently mounted on said table, a controller support pivotally carried by said bracket to swing from operative to inoperative position and formed with a slideway, an electric sewing machine motor-controller having a casing slidably received in said slideway, and coacting means on said controller support and controller casing to lock the latter in said slideway.

6. A motor-controller support for an electric sewing machine cabinet comprising, a bracket having an attaching base and arms disposed at an angle to said base, a plate hinged to said arms and formed with a motor-controller-receiving slideway, and coacting detent means on said plate and one of said arms to retain said plate in a predetermined position relative to said bracket.

7. A motor-controller support for an electric sewing machine cabinet comprising, a bracket having an attaching base and arms disposed at an angle to said base, a plate hinged to said arms and formed with a motor-controller-receiving slideway, coacting detent means on said plate and one of said arms to retain said plate in a predetermined position relative to said bracket, and spring means to yieldingly hold said detent means in coacting relation.

8. A motor-controller for an electric sewing machine cabinet comprising, a controller unit having a casing, a rheostat within said casing, a movable member carried by said casing and connected to operate said rheostat, said casing having a lug, and a support for said controller unit having a slideway within which said controller unit has a limited lateral play, a spring in said slideway bearing laterally against the controller casing to absorb said lateral play, and a lug on said support coacting with the lug on said controller casing to releasably lock said controller unit in said slideway, said lugs being so positioned as to be disengaged by lateral movement of said controller unit in said slideway in a direction opposed to said spring.

9. The combination with a sewing machine table having legs, a top, and side wall members defining a cavity for reception of the sewing machine head when not in use, of a sewing machine motor-controller support hinged to said table to swing about a horizontal axis disposed in said cavity from an operative position below said cavity to an inoperative position concealed within said cavity, and a sewing machine motor-controller detachably mounted on said support and having a movable member engageable by the knee of an operator when said support is in operative position, said controller having a base adapted to rest upon the floor for foot operation.

10. The combination with a sewing machine motor-controller having a flat bottomed casing, a rheostat within said casing and an operator-influenced member at the top side of said casing connected to operate said rheostat, of a sewing machine table, and a motor-controller support carried by said table and formed with a slideway detachably and slidably receiving said motor-controller.
